UNITED STATES PATENT OFFICE.

ALBERT LAMBERT CUDEY, OF PARIS, FRANCE, ASSIGNOR TO THE SOCIÉTÉ CUDEY & COMPAGNIE, OF FONTAINE-LE-BOURG, FRANCE.

FABRIC HAVING METALLIC TEETH OR WIRES SECURED THEREIN.

SPECIFICATION forming part of Letters Patent No. 669,509, dated March 12, 1901.

Application filed September 22, 1900. Serial No. 30,815. (No specimens.)

To all whom it may concern:

Be it known that I, ALBERT LAMBERT CUDEY, manufacturer, of 84 Boulevard Rochechouart, in the city of Paris, Republic of France, have invented Improvements in Fabrics Having Metallic Teeth or Wires Secured Therein, of which the following is a full, clear, and exact description.

This invention relates to improvements in fabrics having metallic wire teeth or wires secured therein. The body portion of this fabric may be in the nature of flat bands or ribbons of caoutchouc, leather, or other suitable materials, such as are used for carding-clothing in carding-engines or as protecting-envelops for the pneumatic tires or the like of road-vehicles of all kinds. Heretofore metallic teeth employed in fabrics of this class have always been formed of smooth wire, and thus at the end of a certain time of service, particularly in the case of wheel-envelops or tire-covers, the teeth become loose and no longer adhere to the band. In order to insure the secure attachment of the teeth to the fabric, this invention consists in using in the manufacture of these bands or fabrics metallic threads or wire having a crinkly or wavy form, the undulations not exceeding in practice the diameter of the wire in lieu of straight or smooth metallic threads or wires extending transversely through the fabrics.

The accompanying drawings show, as examples only, bands provided with metallic teeth secured according to this invention.

Figure 1 shows in longitudinal section a protecting-cover of a tire of a velocipede or motor-car wheel, and Fig. 2 shows in section the rim of a wheel and tire provided with a cover of this kind. Fig. 3 shows a spinning or combing card, the teeth of which are secured according to this invention.

Like letters of reference indicate corresponding parts in the several figures.

a is the body portion of the fabric, which may be of caoutchouc, leather, or like flexible material and in which the teeth are fixed or secured. In the case of the tire-cover, Figs. 1 and 2, these teeth are solely intended to consolidate the said envelop or band, and they do not project beyond the surface of the latter. As shown, these teeth are preferably

of substantially **U** shape in general contour and are bent, waved, or undulated throughout at least a portion of the extent of each so-called "tooth" in such a manner that it is 55 solidly fixed or secured in the material constituting the body portion of the band. Thus the bends or waves can be arranged either on the whole of the tooth, as shown at *b*, Fig. 1, or, on the contrary, on the two vertical 60 branches only of the tooth, as shown at *c*. The body portion, of leather or caoutchouc, thus reinforced by the teeth *b* or *c*, which extend through the same transversely to the plane thereof, is itself applied to wheels in the 65 same manner as the envelops or tire-cover usually employed. Fig. 2 shows an envelop or tire-cover *a* of this class consolidated by sheaths of sheet-iron *k* and inclosing the air-tube *d*. The envelop is fixed to the wheel- 70 rim *e* by means of wires *f* or the like; but this method of securing it is only given as an example, and the same can be replaced by a method employing hooks or by any other convenient method.

It is evident that this invention is independent of the arrangement of the accessory parts and solely comprises the special arrangement of the teeth above described.

In Fig. 3, which represents a spinning-card, 80 the teeth fixed in the ribbon or band *a* extend transversely therethrough and project beyond the surface of this band in order to constitute the card in the ordinary manner; but the part of the wire which is embedded in the 85 band *a* is formed, as hereinbefore set forth, of bent or waved wire. These bends or waves can exist on the whole of the embedded part, as shown at *h*, or on the transversely-extending parts only of the tooth, as shown at *i*. 90

The shape of the exterior parts of these teeth is absolutely independent of this invention and depends upon the purpose for which the tooth is to be employed.

Bands or strips made in accordance with 95 my invention can be applied, as stated, not only to "cards," properly so called, with projecting teeth, but in all cases where metallic threads or wires are to be fixed or secured to bands or ribbons of caoutchouc, leather, or like flexible material. Bands, strips, or ribbons provided with teeth similar to those

shown in Fig. 1 are particularly applicable for use in making joints of all kinds or as packing for tubes, machines, and the like, and also for the soles of boots and shoes, beltings, 5 burnishers, and the like.

Having described my invention, what I claim, and desire to secure by Letters Patent, is—

A fabric comprising a body portion and substantially U-shaped wires extending transversely through said body portion, said wires

being undulated throughout at least a portion of their extent.

The foregoing specification of my improvements relating to the fixing or securing of metallic teeth or wire in caoutchouc, leather, or other fabric signed by me this 10th day of September, 1900.

ALBERT LAMBERT CUDEY.
